WEB DISPENSER MOUNTING

Earl A. Gilling, Frank P. Vaughan, and Albert G. Krueger, Green Bay, Wis., assignors to Bay West Paper Company, Green Bay, Wis., a corporation of Wisconsin

Application February 20, 1936, Serial No. 64,986

5 Claims. (Cl. 242—55.2)

This invention relates to improvements in web dispenser mountings, and has particular reference to an assembly of core and bracket parts.

It is the primary object of the invention to provide a novel and improved core and bracket assembly of such a nature as to facilitate the mounting of the core and to assure that rolls of webbing mounted in the dispenser for service therein will have authorized cores. In other words, it is an object of the invention to prevent or discourage the use of the device for dispensing competitive web material. Another purpose is to provide a novel and improved slide bracket for mounting the cores upon which the rolls of webbing are to be carried for dispensing purposes.

In the drawing:

Figure 1 is a perspective view of dispensing apparatus embodying this invention as it appears with the front of the case open to expose the core and bracket assembly, portions of the core being broken away to an axial section.

Figure 2 is a view taken in section on the line 2—2 of Figure 3.

Figure 3 is a view taken in section on the line 3—3 of Figure 2.

Like parts are identified by the same reference characters throughout the several views.

The dispensing mechanism per se forms no part of the present invention and will be covered in a companion application, Serial No. 76,442 filed April 25, 1936, by Frank P. Vaughan, Albert G. Krueger and Norman J. Slye, and entitled "Dispensers for paper articles".

All of the parts are preferably assembled upon the back 4 for a dispenser case 5. The back is provided with means whereby it is suitably mounted upon the wall or other support, and in addition to the usual marginal flanges 6, 7 and 8, it carries a wider supporting flange 9 upon which the case 5 is pivoted by means of the pintle 10. When the case is swung forwardly and downwardly about pintle 10 to the position illustrated in Fig. 1, the bracket and core assembly mounted on the back 4 is fully exposed.

The core 15 may be made of fibre or paper board, or the like, in the form of a tubular roll into one end of which is pressed the fitting 16. This fitting has a number of arms 17 arranged to engage the inner periphery of the core roll 15 and provided with expressed lugs or teeth at 18 which will engage the material of the core roll to prevent the fitting from being easily extracted therefrom. Beyond the arms 17 the fit-

ting provides an annular bead 19 terminating in a radial flange at 20.

Rigidly secured to the back 4 is the bracket arm 22 which has a saucer-shaped circular recess at 23 to receive the bead portion 19 of the fitting 16 and thereby to provide rotatable support for the core 15.

At the opposite end of the core, the core engages over the exterior periphery of an inwardly formed boss 24 which is provided in the adjustable arm 25. The material of the boss portion 24 of arm 25 is punched through at 26 to make an irregular projection which is eccentrically located on the boss so that if any attempt be made to provide a wooden roller as a support for the conventional core, such roller will tend to rotate upon the punch projection 26 which, being eccentric, will give the roller an erratic movement and prevent it from operating satisfactorily

20

In order that the core 15 may be readily inserted and removed between the brackets 22 and 25, the bracket 25 is preferably made extensible with reference to the back 4 of the dispenser. Bracket 25 is formed with an integral slide 25 portion 27 operating through the flange 8 at the back and guided between the ears 28 and 29 which are formed forwardly from the integral metal of the back 4. Between the ears 28 and 29 there is a strap 30 connected integrally with the metal of the back at its ends and free thereof along its side margins for resilience. A lug 31 struck up from strap 30 fits into a groove 32 in the slide member 27 to serve as a stop to limit the movement thereof. A similar lug 33 35 may be engaged in an aperture 34 of the slide by bending the strap rearwardly to permit the slide to pass over lug 33 until aperture 34 is registered therewith. The registration is effected when the slide 27 is fully retracted so that the 40 bracket arms 22 and 25 are both engaged with the core member 15.

The engagement of lug 33 in the aperture 34 of the slide holds the core member in place pending the closing of the dispenser casing 5 against the back. When the dispenser casing is moved upwardly to the position illustrated in Fig. 3, its sides confine the bracket arms 22 and 25 and reinforce such arms against separation. Thus the core cannot be removed or replaced without first dropping the case to the position shown in Fig. 1 and then bending the strap 30 to release its lug 33 from aperture 34, whereupon the slide 27 will be drawn outwardly to the position illus- 55

trated in Fig. 1 to free the ends of core member 15.

It will be noted that due to fitting 16 the core member 15 is engaged with the interior of the boss 23 of bracket 22, although the opposite member is engaged with the exterior of the boss 24 and bracket 25. The two bosses are therefore of differing diameters and no ordinary core will fit the brackets. If an effort be made to mount 10 an ordinary core upon a wooden roller, the eccentrically located projection 26 will tend to permit such a roller to rotate upon a center other than its axis, whereby the roll of web carried thereby will be dislocated within the cabinet and 15 will not feed properly through the dispensing mechanism.

We claim:

1. A dispenser comprising the combination with a mounting member, of a first bracket arm 20 projecting therefrom, a slide movable laterally of said mounting member with respect to said arm, a second bracket arm carried by said slide, means on said arms for removably supporting a core, and a dispenser case within which said arms 25 are receivable when engaged with a core, said case having wall portions engageable about said arms for the confinement thereof against release of a core when said arms have been received into the case.
- 30 2. A dispenser comprising the combination with a mounting member, of a first bracket arm projecting therefrom, a slide movable laterally of said mounting member with respect to said arm, a second bracket arm carried by said slide, 35 means on said arms for removably supporting a core, and a dispenser case within which said arms are receivable when engaged with a core, said case having a width only slightly greater than the spacing between said arms in the contracted 40 position of said slide, whereby said case is substantially in face contact with said arms to prevent separation thereof when said case is positioned against said support.

3. In a device of the character described, the 45 combination with a supporting back having a

laterally extending strip connected with the back at its ends and free thereof along its margin, of a tongue projecting forwardly from said strip, means carried by the back and providing a guideway longitudinally of said strip, a slide reciprocable along said guideway and provided with means adapted for interlocking engagement with said tongue, said strip being yieldable to permit such engagement, and bracket arms carried respectively by said support and said slide and 10 projecting therefrom in spaced relation and provided with core supporting means.

4. In a dispenser, the combination with a support having a bearing surface against which the end of a roll is adapted to abut, said surface being embossed to provide a cup-shaped socket, a roll carrying core of smaller diameter than said socket terminating substantially flush with said surface, and a fitting having means engaged within the end of said core, said fitting projecting 15 from said means and being beaded annularly back upon itself to provide an external bearing surface fitting said socket, whereby to position said core in such manner that the roll mounted thereon will substantially abut said first mentioned surface.

5. In a dispensing device, the combination with a supporting back comprising a plate member, of a bracket arm fixed adjacent one side of said plate member, means formed integrally with 30 said plate member providing a guideway adjacent the other side thereof, a slide member reciprocable along said guideway, a second bracket arm carried by said slide member for movement to and from the first bracket arm, a spring plate 35 formed integrally with one of said members and connected integrally therewith at both of its ends, and a latch element carried by an intermediate portion of said strip, the other of said members having means cooperable with said latch element 40 for adjustably fixing the position of said slide member.
